MUSICAL INSTRUMENT

James A. Koehl, Chicago, Ill.

Application December 7, 1940, Serial No. 368,976

23 Claims. (Cl. 84—171)

This invention relates to piano attachments and has for its primary objects the provision of means for utilizing the playing keys of any standard piano to produce sustained tones.

Another object is to provide a device of the class and for the purpose aforesaid which may be readily attached to the piano while in no manner interfering with the ordinary operation of the various mechanisms of the instrument.

A still further object is the provision of a device enabling sustained tones and piano tones to be played at one and the same time when depressing playing keys in the treble and bass registers respectively of the instrument's keyboard, the forms and arrangement of elements of the device being such that piano tones or sustained tones can be elicited from either of said registers and a change over from one register to the other instantly effected at the will of the player.

Another object is the provision of a means actuatable from the keyboard for selectively rendering the hammers of the piano respectively responsive and non-responsive to depression of the playing keys according as particular musical effects are desired.

A still further object is to provide an attachment which is selectively actuatable to enable the entire keyboard of a piano to be used either for the production of piano tones or sustained tones as desired.

Another object is to provide an attachment for pianos, enabling any well known frequency generating devices to be used for the production of sustained tones of any desired timbre.

While I prefer to employ means responsive to each individual playing key of a piano for producing a sustained tone of the fundamental pitch of the note associated with said key, whereby and as compared with the frequency range of the short manual of an organ, tones in the frequency range of both said short manual and also the pedal board of the organ can be produced as desired, it shall be understood that I am not to be limited in this respect and that while superior results can be had when using a piano having eighty-eight keys ranging from note A₃ at the bottom to note C⁴ at the top of the keyboard, a piano whose keyboard has a lesser number of octaves can be satisfactorily employed.

A still further object is the provision of an attachment which gives to the piano musical advantages which heretofore could be had only with separate instruments, i. e. a piano and an actual organ or an instrument adapted electrically to produce organ tones, thereby economical-

ly combining two instruments in one and materially reducing the cost of instruments for the electrical production of sustained tones.

Other objects and advantages will appear from the following description and upon reference to the accompanying drawings, in which:

Figure 1 is a schematic view in top plan illustrating the attachment applied to a piano keyboard;

10 Figure 2 is a transverse section through a portion of a piano illustrating the application of an electric switch to a playing key and showing the hammer action for said keys and the means for selectively rendering the hammer non-responsive to depression of said key;

15 Figure 3 is a diagrammatic illustration of the generators for producing complex waveforms of potentials at the tone frequencies of different notes of the musical scale and the switches for rendering said waveforms effective upon an electroacoustic translating device;

20 Figures 4 and 5 are views partly in transverse section and partly in elevation of a portion of piano keyboard showing a slightly modified form 25 of my invention.

Upon reference to the form of my invention shown in Figures 1-3, inclusive of the accompanying drawings, 5 represents a conventional piano keyboard comprising eighty-eight playing 30 keys, ranging from note A₃ below middle C to note C⁴ above middle C.

Each individual key 6 of the keyboard 5 has associated therewith a conventional hammer action 7 as shown in Figure 2. While my invention is shown applied to a grand piano, this shall not be construed as a limitation. As a matter of 35 fact, in the majority of cases such attachments will be applied to the more commonly used vertical pianos. Between the hammer rail 8 and the butt 9 of the hammer 10 is a felt covered

40 lifting bar 11 of a vertically movable yoke 12, the longitudinal top bar 13 of which has wiping engagement with a cam 14. Said cam is manually actuatable and is mounted upon a rod 15 which projects forwardly and to the keyboard 45 where it may be conveniently reached by the hand of the player and manipulated. When moved towards the player the cam is retracted from said bar 13 and the hammer 10 is free to be operated in the usual manner.

When moved away from the player, the yoke is elevated and the bar 11 lifts the hammer to a position where it is non-responsive to the hammer action when the playing key is depressed.

50 55 The damper head 14 is a part of a conven-

tional damper mechanism which functions in the well-known manner. It will suffice to say that when skillfully used in conjunction with my attachment pleasing musical effects will be produced.

In Figure 3, oscillation generators designated A#2, B2, C and C# are shown. In the instant example, I have stated that my invention is applied to a piano, the keyboard of which has eighty-eight playing keys ranging from note A3 in the bass section to note C4 in the treble section. Thus, the bass section embraces thirty-nine notes, whereas the treble section embraces forty-nine notes. I make particular reference to this for the reason that for each note in the gamut, I preferably employ an electrical frequency generator which produces a predetermined complex waveform of alternating current of the fundamental pitch of said note. If when translated into sound said waveform of alternating current has the characteristics of an organ tone, it follows that each key of the piano will have at its command two distinct tones, one of which is an actual piano tone produced in response to the hammer action when depressing the key and the other an electrically produced organ tone produced by translating said current into acoustic energy.

Referring now to Figure 1 of the accompanying drawings, the block diagram 15 represents a frequency generating assembly comprising twelve frequency dividing systems of any well known construction. Each said system may comprise vacuum tube oscillators, gas content tubes or the equivalent thereof. The systems respectively generating waveforms of alternating current at the tone frequencies of notes A, A#, B and C will each consist of eight individual oscillation generators electrically coupled to one another in cascade fashion by tuned circuits such that their output frequencies are in octave relation. The systems respectively generating frequencies corresponding to notes C#, D, D#, E, F, F#, G and G#, will each thereof consist of seven oscillation generators similarly coupled together in cascade fashion by tuned circuits to secure octave separation of their respective output frequencies. Such frequency dividing systems may themselves be controlled by master oscillators, functioning to impress upon the control grids of the respective first stages, signals which determine the frequency of oscillation of said first stages. As I make no claim to these systems apart from their broad combination with other elements of my invention, it will suffice to say that each individual oscillation generator is actuatable to deliver a waveform of alternating current to the input circuit of an amplifier upon a circuit being established between said generator and said amplifier. This is accomplished by means of a switch 16 for and controlled by each individual playing key as shown in Figures 2 and 3, said switch comprising a grounding contact 17 with which a metallic leaf spring 18 is engaged when the key 6 is elevated, and a contact 19 which is engaged by said spring in response to depression of said key. The springs 18 of the respective switches 16 connect with a common output conductor 20 of an electroacoustic translating system 21. The spring 18 of each individual switch is connected by a circuit path 31 with an oscillation generator producing a frequency corresponding to the note associated with the playing key of which said switch is a part. 75

The entire switch organization is mounted in a casing 23 secured at 24 to the bottom board 25 of the piano case 26, and I particularly call attention to the feature of my invention which consists in providing for each playing key of the piano, a vertically movable pin 27 which passes into the case 26 and has its upper felt faced end 27a in yielding engagement with the under surface of the key as shown to advantage in Figure 2. The lower end of the pin passes into the casing 23 and bears freely against the upper face of the free end of the spring 18. In this manner and to effect application of my attachment to any well known piano, it is simply required that vertical guide holes 28 be formed in the bottom board 25 of the piano case, such that there is one such hole beneath each individual playing key, in each of which is a switch controlling pin 27. By reason of this simple arrangement of the elements no great changes are required to be made to any parts of the piano. The holes are preferably arranged in a longitudinal row in said board 25 of the piano case so as to coincide with a corresponding arrangement of the switch pins 27 and enable free vertical insertion of said pins in their respective holes when securing the casing 23 to the piano.

In Figure 3, it is assumed that the oscillation generator A#2 is one of a set of eight similar oscillation generators coupled to each other to secure octave separation of their respective output frequencies. In this manner, frequencies for all the A# notes throughout the gamut of the keyboard are provided. In like manner the B2 oscillation generator is one of a set of eight similar oscillation generators which supply frequencies for all B notes. Similarly, the oscillation generator C is one of a set embodying eight oscillation generators which furnish frequencies for all of the C notes. The oscillation generator C#, however, is one of a set embodying but seven such oscillation generators. The control grid 29 of each of said oscillation generators is connected with a path 30 which supplies said grid with a controlling signal. A waveform of output voltage from each oscillation generator is adapted to be delivered to a circuit path 31 which connects with the common output conductor 20, the latter connected to the aforementioned translating system 21. Delivery of said output voltage to said common conductor is effected upon close circuiting the key controlled switch 16 which is individual to said path 31. In each of said paths 31 is a normally open circuited switch 32. Said switches 32 are arranged in separate banks or gangs, such that there is one such bank or gang of switches for all playing keys in the bass register of the keyboard 5 and one such bank or gang of switches for the keys in the treble register of the piano. Thus, there will be thirty-nine switches 32 in the bank of switches for the keys in said bass register and 49 such switches in the bank for said treble register. All switches in each said bank of switches are adapted to be simultaneously controlled by a common actuator 33. When the switches are close circuited, output voltages from the generators in circuit therewith will be impressed upon said common output conductor 20 upon close circuiting the switches 16 in said paths 31. In Figure 3 wherein four oscillation generators are shown, the generators A#2 and B2 are associated with keys in the bass register of the keyboard. Generators C and C# are associated with keys in the treble register. Reference is made thereto in order that

it will be understood that all generators in any selected register are adapted to be either simultaneously open or close circuited in the system according as particular musical results are desired to be obtained. Similarly, there will be two cams 14 and a corresponding number of hammer lifting yokes 12 such that one thereof controls all hammers in the bass register and the other all hammers in the treble register.

Having described the essential features of 10 construction of my invention, the operation of the embodiment shown in Figures 1-3, inclusive, is described as follows:

When the instrument is played exclusively as 15 a piano, both banks of switches 32 are open circuited. The respective cams 14 are preferably retrieved from their yokes, thereby freeing the hammers 10. The keys may now be played in the usual manner.

When the instrument is played as an organ the 20 hammers 10 are preferably but not necessarily adjusted to render same non-responsive to depression of the playing keys. The switches 32 in both banks of said switches are close circuited. Upon depressing any of the playing keys, paths 25 31 between respective oscillation generators and the common output conductor 28 will be close circuited in response to actuation of the key switches 16. Waveforms of voltages produced by said generators will be impressed upon the input circuit of the system 21 and translated into sounds which may be sustained as long as the keys are held depressed.

Sustained tones can be played as a melody with the right hand and a piano accompaniment with the left hand. This is accomplished by open circuiting the switches 32 in the bass register, close circuiting the switches 32 in the treble register and preferably but not necessarily adjusting the hammers 10 in the treble section to render same non-responsive to depression of the playing keys. While I suggest dividing the keyboard into treble and bass sections, in either of which sustained tones may be produced, and whereby a change over from one register can be made as desired, it shall be understood that in certain embodiments of my invention, the production of sustained tones may and in all probability will be confined to the treble section and may embrace as many octaves as required for given musical results.

New and interesting musical effects are readily obtainable by retrieving the cams 14 and freeing the hammers 10 to render the latter responsive to depression of the playing keys, and close circuiting the switches 32 of either or both banks of said switches. With the elements thus adjusted, the playing keys may be depressed at any desired velocity according as particular musical results are desired to be produced. When the velocity of the keys is low, the piano tones are barely audible. Audibility increases as the key velocity increases. Piano tones and sustained tones are thereby simultaneously produced and by holding the keys depressed after sounding the piano tones, many musically useful effects are had in that sustained tones of the same pitch as the piano tones may be maintained at constant amplitude for any desired interval of time by holding the keys depressed. By controlling the potentiometer 33 the loudness level of the sustained tones can be regulated as desired. By controlling the velocity of the playing keys and also controlling the potentiometer 33, additional novel effects are possible.

While I preferably employ means of the nature aforementioned for selectively rendering the hammers 10 non-responsive to depression of the playing keys, this is not absolutely necessary, and I do not propose to be limited in this respect.

Other desirable musical effects are had by simply controlling the damper mechanism of the piano, similarly controlling the velocity of the playing keys and regulating the potentiometer 33.

In order that unnecessary complications may be avoided, I have disclosed means whereby but a single complex waveform of output voltage is derived from the oscillation generators. The output path 31 of each generator connects with the screen grid of the generator which supplies a waveform which is rich in harmonics. The path 31, may, however, lead from the plate of the generator and in such event an entirely different waveform of output voltage is had. Any well known system of stops may be connected in the network in which said generators are connected, whereby any desired waveform of output voltage can be rendered effective upon the system 21. 20 No claim is made to any of these features as it is within the province of anyone skilled in the art to employ such stops according as particular timbres are desired to be produced.

While I show oscillators as frequency sources 30 for the production of sustained tones, it shall be understood that this is by way of illustration only and that any well known system can be substituted for said oscillators without departing from the spirit and intention of my invention.

In the form of my invention shown in Figures 4 and 5, I employ for each white key 6a of the piano keyboard, an electric switch 35 embodying a vertically tiltable contact element 36 having an extension 36a disposed above and in spaced relation to the upper face of the front rail 37 of the case of the piano and in the path of the projection 38 of the key. A frequency input circuit wire 39 is connected to said contact element and as shown said element is normally maintained in an open circuit condition of adjustment by a light spring 40. Upon depressing the key, the element 36 makes electrical contact with an output circuit completing element 37b adapted to be connected to the input of an amplifier as in the first described embodiment of my invention. 40 Switches 35 for all of said white keys are mounted in a small longitudinally disposed casing 41 secured to the piano case as shown.

55 The black keys 7a are each provided with a yieldingly depressed element 42 having a contactor 43 adapted to be connected with a frequency generator. The element bears lightly upon the upper face of the black key at the back end thereof and is held in open circuit by the key. In the path of descending motion of the element 42 which motion occurs when depressing key 7a, is a contact 44 which is adapted to be connected to the input circuit of said amplifier. 60 Switches for all of said black keys are mounted in a small longitudinally disposed casing 45 upon the case of the piano as shown in Figure 5.

70 The term "vibrators" employed in the here-to annexed claims shall mean the strings of the herein disclosed piano or their functional equivalent.

To the best of my knowledge, it is broadly new and novel to combine in a single musical instrument key-controlled means for producing audible

sounds by vibrating tuned resonant bodies such as piano strings and utilizing the keys of the instrument for producing sustained sounds in the same pitch relation as sounds produced by said tuned resonant bodies, whereby said different types of sounds can be employed either separately or together for the production of versatile musical effects and whereby, for example, a piano can be readily converted into an entirely practical instrument for producing organ tones, and I therefore reserve to myself a broad range of equivalents of the mechanical and electrical elements herein employed.

In those instances wherein my invention is manufactured as an original part of a piano, the key controlled switches 18 can be mounted inside the case of the instrument so as to be responsive to depression of the playing keys. The stop switches 32 may be mounted in any suitable manner upon the case where access can be had thereto as desired.

When the key-controlled switches are mounted as shown in Figure 2, the stop switches 32 may be housed in the casing 23 and the actuators 33 mounted upon the front of said casing where they may be conveniently reached by the player.

What I claim as my invention is:

1. A musical instrument comprising mechanism for producing percussive tones in the pitch relation to notes of the even tempered musical scale, said mechanism including playing keys associated with different notes, and means for producing sustained tones in the same pitch relation as said percussive tones and including mechanism related to and responsive to depression of any playing key for rendering effective upon an electrical sound producer a waveform of alternating current having the tone frequency of the note associated with said key and for sustaining the resultant tone for such interval of time as the key shall remain depressed.

2. A musical instrument comprising vibrators adapted respectively to produce complex waveforms of audible vibrations at the tone frequencies of different notes of the musical scale, electrical generators respectively producing complex signals at the fundamental frequencies of said audible vibrations, means for translating said signals into audible sounds, an actuator for each individual vibrator, a playing key for operating said actuator, and an electric switch also actuatable by said key for close circuiting said translating means with a generator producing a signal having the frequency of the note associated with said key.

3. A musical instrument comprising vibrators adapted respectively to produce audible vibrations at the tone frequencies of different notes of a musical scale, electrical generators respectively producing tone signals at the same fundamental frequencies as said audible vibrations, playing keys, such that there is one such key for each of said notes, means for translating said signals into sounds, and respective means for and actuatable by and upon depression of the key at low velocity for close circuiting said translating means with a generator producing a signal having the vibration frequency of the note associated with said key and actuatable upon the velocity being increased to cause an audible vibration of the frequency of said note to speak during translation of said signal into audible sound.

4. A musical instrument comprising vibrators adapted respectively to produce complex waveforms of audible vibrations at the tone frequen-

cies of different notes of the musical scale, electrical generators respectively producing signals at the fundamental tone frequencies of said audible vibrations, means for translating said signals into audible sounds, an actuator for each individual vibrator, a playing key for operating said actuator, an electric switch also actuatable by said key for close circuiting said translating means with a generator producing a signal having the frequency of the note associated with said key, and means for selectively rendering the actuators inactive relative to said vibrators upon depressing said playing keys.

5. In a musical instrument employing playing-key-controlled vibrators respectively producing audible vibrations at the tone frequencies of different notes of the musical scale, and an electroacoustic translating means, electrical generators respectively producing signals at the frequencies of said audible vibrations, means for and controlled by each playing-key upon depression thereof for close circuiting said translating means with a generator producing a signal at the tone frequency of the note associated with said key, and means selectively actuatable to render the vibrators non-responsive to depression of said keys.

6. In a musical instrument employing playing-keys associated with different notes of the musical scale, vibrators actuatable in response to depression of said keys and respectively producing audible vibrations at the tone frequencies of said notes; an electro-acoustic translating system, electrical sources respectively supplying tone signals at the frequencies of said audible vibrations; means selectively actuatable to render the vibrators non-responsive to depression of said keys, and means responsive to depression of selected keys for rendering signals at the frequencies of notes associated with said keys effective upon said translating means throughout such period of time that said keys shall remain depressed.

7. The combination with a musical instrument having a keyboard, the playing keys of which are associated with different notes of a musical scale, and means individual to and actuatable by each playing key for producing a percussive sound of the frequency of the note associated with said key, of mechanism for each individual playing key for electrically generating a signal of the same frequency as the percussive sound produced by the same key, and means in coaction with the signal generating mechanism and said key for converting said signal into sound to produce with said percussive sound a timbre which is a mixture of the two sounds.

8. The combination with a musical instrument having a keyboard, the playing keys of which are associated with different notes of a musical scale, and means individual to and actuatable by each playing key for producing a percussive sound of the frequency of the note associated with said key, of mechanism for each individual playing key for electrically generating a signal of the same frequency as the percussive sound produced by the same playing key, and selectively active means in coaction with the signal generating mechanism and said key for converting said signal into sound to produce with said percussive sound a timbre which is a mixture of the two sounds.

9. The combination with a musical instrument having a keyboard, the playing keys of which are associated with different notes of a

musical scale, and means individual to and actuatable by each playing key for producing a percussive sound of the fundamental frequency of the note associated with said key, of mechanism for each individual playing key for electrically generating a signal of the same frequency as the percussive sound produced by the same key; means in coaction with said signal generating mechanism and said key and responsive to actuation of the latter for converting said signal into sound to produce with said percussive sound a timbre comprising a mixture of the two sounds, and means for controlling the amplitude of one of said sounds relative to that of the other sound.

10. The combination with a musical instrument having a keyboard, the playing keys of which are associated with different notes of a musical scale, and means individual to and actuatable by each playing key for producing a percussive sound of the frequency of the note associated with said key; of mechanism for each individual playing key for electrically generating a signal of the same fundamental frequency as the percussive sound produced by the same key; means in coaction with said signal generating mechanism and said key and actuatable by the latter for converting said signal into sound to produce a timbre comprising a mixture of both said sounds, and means for controlling the amplitude of one of said sounds relative to that of the other sound, said key actuatable means serving to sustain said one sound as long as playing pressure is applied to said key.

11. The combination with a musical instrument having a keyboard, the playing keys of which are associated with different notes of a musical scale, and means individual to and actuatable by each playing key for producing a percussive tone of the frequency of the note associated with said key; of mechanism also actuatable by each individual playing key for electrically generating a signal having the frequency of the note associated with said key and a waveform different from that of the percussive tone produced by the same key, and means for rendering said signal effective upon an electrical sound producer to produce a tone simultaneously with production of said percussive tone and provide therewith a timbre which is a combination of both said tones.

12. In a musical instrument for producing musical sounds of different timbre, some of which have natural periods of decay, a keyboard; means actuatable from the keys of said keyboard for mechanically producing musical sounds having the aforementioned natural periods of decay; mechanism actuatable from the keys of said keyboard for electrically producing sounds of the same pitch as sounds being mechanically produced at any instant; and means associated with and controlled by said keys for sustaining said electrically produced sounds as long as desired after decay of mechanically produced sounds of the same pitch.

13. In a musical instrument, a keyboard, mechanism actuatable from the keys of said keyboard for producing piano tones bearing the pitch relation to musical notes associated with different keys of said keyboard; and means for enriching said piano tones, said enriching means comprising a generator of alternating current for each individual key of said keyboard, the waveform of said alternating current having a higher harmonic content than that of the piano tone

produced by the same key and being of the same frequency as said piano tone, electroacoustic mechanism for translating said current into sound, and means associated with and controlled by the keys of said keyboard for sustaining sound produced by the translating mechanism as long as desired.

14. The combination with a piano having a keyboard and means associated with each individual key thereof for producing a tone of the frequency of the note associated therewith, of a generator of alternating current associated with each individual key of said keyboard for continuously producing alternating current of the frequency of the note associated with said key but of a waveform different from that of the piano tone produced by the same key, and means enabling selective conversion of said alternating currents into sounds.

15. In a musical instrument, the combination with a piano having a keyboard and means actuatable by each individual key thereof for producing a piano tone of the frequency of the note associated with said key, of an electroacoustic translating device, means including pulsation generators for generating waveforms of voltages at the frequencies of notes associated with different keys of said keyboard and actuatable when depressing selected keys to render said waveforms effective upon said translating device to produce sounds of the same frequencies as the notes associated with said keys, mechanism for preventing translation of certain of said voltages when playing selected keys of said keyboard thereby enabling exclusive production of piano tones by said selected keys, and means for varying the amplitude of sounds produced by the translating device relative to the amplitude of piano tones of the same frequency.

16. The combination with a piano having a keyboard and means actuatable therefrom for producing piano tones in the pitch relation to musical notes associated with different keys thereof, of an electroacoustic translating device; a generator of alternating current for each individual playing key of said keyboard for continuously producing alternating current of the fundamental frequency of the piano tone associated with said key and waveform different from that of said piano tone and adapted upon depression of said key to actuate said translating device and effect production of sound during production of a piano tone by said key, and means for sustaining the sound produced by the translating device as long as desired and at any selected amplitude.

17. The combination of a musical instrument employing a keyboard and mechanism actuatable by the different keys thereof for mechanically producing musical sounds having natural periods of decay and pitches corresponding to notes of a musical scale associated with said keys; and mechanism for generating and converting alternating voltages into sounds, said mechanism including a generator for and associated with each individual playing key of said keyboard for continuously producing alternating voltage of the tone frequency as the note associated with said key, means responsive to depression of the keys for converting the generated voltages into audible sounds; and means coacting with the generating and converting means for controlling the amplitude of sounds resulting from said conversion.

18. A musical instrument having a keyboard, a vibratile member for each individual key of the

keyboard for producing an audible sound of the tone frequency of the note associated with said key, and means associated with and operating in response to each successive depression of a key for setting a respective vibratile member in vibration, and continuously operating mechanisms, one for each playing key of said keyboard, for electrically producing a signal of the pitch of the note associated with said key and including means associated with and responsive to actuation of the key for effecting conversion of said signal into sound and for continuing said conversion as long as the key remains depressed.

19. A musical instrument having a keyboard, means individual to each playing key of said keyboard for producing a piano tone of predetermined frequency; means also individual to each of said playing keys for electrically producing a tone signal of the frequency of the piano tone associated with the same key; an electrical sound producer for conversion of said signals into audible sounds; and mechanisms actuatable to render either the first or second-named means active independent of the other for the production of sounds when playing selected playing keys.

20. A musical instrument having a keyboard, means individual to each playing key of said keyboard for producing a piano tone of predetermined frequency, means also individual to each of said playing keys for electrically producing a tone signal of the frequency of the piano tone associated with the same key, an electrical sound producer for conversion of said signals into audible sounds, and mechanisms selectively actuatable to render the first and second-named means independently or conjointly active for the production of sounds when playing selected playing keys.

21. A musical instrument having a keyboard, means individual to each playing key of said keyboard for producing a piano tone of predetermined frequency, means also individual to each

of said playing keys for electrically producing a tone signal of the frequency of the piano tone associated with the same key, an electrical sound producer for conversion of said signals into audible sounds, and mechanisms selectively actuatable to render either the first or second-named means active for the production of sounds when playing keys of a selected portion of the keyboard.

22. A musical instrument having means, including a keyboard, for producing piano tones in the pitch relation to musical notes associated with the different playing keys of said keyboard, and means for producing waveforms of alternating voltages in the same pitch relation as the aforementioned piano tones and of the timbre of organ tones and for converting same into audible sounds, said second-named means associated with and coacting with said first-named means and both said means associated with the keys of said keyboard so that each individual key has at its command a piano tone and an organ tone of the same pitch when playing any selected keys of said keyboard.

23. A musical instrument having means, including a keyboard, for producing piano tones in the pitch relation to musical notes associated with the different playing keys of said keyboard, and means for producing waveforms of alternating voltages in the same pitch relation as the aforementioned piano tones and of the timbre of organ tones and for converting same into audible sounds, said second-named means associated with and coacting with said first-named means and both said means associated with the keys of said keyboard so that each individual key has at its command a piano tone and an organ tone of the same pitch when playing any selected keys of said keyboard, and means selectively actuatable to render the instrument operable for the exclusive production of tones of either of said timbres.

JAMES A. KOEHL.
